CLAIM

The ornamental design for a floating nut anchor for concrete construction, as shown and described.

DESCRIPTION

FIG. 1 is a perspective view, from the front, of a floating nut anchor for concrete construction, showing my new design; FIG. 2 is a top end view thereof, the other end view (not shown) being identical; FIG. 3 is a left side view thereof, the other side view (not shown) being symmetrical; and, FIG. 4 is a back view thereof.

The portion of the interior not shown in FIG. 1 forms no part of the claimed design.

The four fasteners disclosed in FIG. 1 have been omitted from FIGS. 2-4 for ease of illustration.
